LIVESTOCK CAR SHUTTER STRUCTURE

James M. Coyner, Madison, Wis.

Application July 14, 1948; Serial No. 38,711

4 Claims. (Cl. 98—6)

1

This invention relates to live stock car shutter structure. By "live stock car," I mean a railway car, truck or other vehicle having slats along its side walls for the ventilation of the car, etc.

Livestock require abundant ventilation during the hot months. Frequently, lack of ventilation in hot weather causes live stock to lose weight and sometimes death is caused by suffocation or overheating. On the other hand, in the cold months, the amount of ventilation provided by the spaced slats on stock cars is entirely too great, and the driving snow, rain and cold winds cause severe injury to the animals being shipped.

To meet the above situation, some shippers endeavor to protect their live stock from the cold by lining the cars with paper or by nailing slats over the open spaces in the car walls. Such protection is not satisfactory because there is usually not enough time to collect material and to attach the necessary protection strips to the car after loading. The cost of material and labor is high, the lining is often destroyed by the live stock, and sometimes the animals are injured by the improvised linings. Finally, the weather may change suddenly and a removal of the linings cannot be accomplished quickly enough to protect the live stock from suffocation and over heating. In long travel across the country, such relatively wide changes in temperature occur, and such linings are impracticable to meet such changes in weather conditions.

An object of the present invention is to provide a live stock car structure in which the ventilation openings may be quickly adjusted to provide the desired ventilation and to exclude air currents, rain, driving snow, etc. Another object is to provide a car shutter structure of extremely sturdy construction which can be readily operated to effect a control of ventilation within the car while, at the same time, avoiding projection of members into the car that might injure the live stock. A still further object is to provide a live stock car structure equipped with movable shutters which may be adjusted in a modicum of time, the shutter structure being an integral part of the car and forming no projecting members that might form a hazard to the live stock or to railway traffic; means being provided for operating the shutters from outside of the cars and at convenient points. Other specific objects and additions will appear as the specification proceeds.

The invention is illustrated, in a single embodiment, by the accompanying drawing, in which Fig. 1 is a broken side view in elevation of a railway car equipped with structures embodying my

2

invention; Fig. 2, an enlarged, detailed, sectional view, the sections being taken as indicated at line 2 of Fig. 1, the shutters being in lowered position; Fig. 3, a view similar to Fig. 2, but showing the shutters in raised or closed position; Fig. 4, an enlarged, transverse, sectional, detailed view, the section being taken as indicated at line 4 of Fig. 1; Fig. 5 is an elevational view of the shutter 13.

In the illustration given, A designates a railway car having its side walls provided with slats indicated by the numeral 10. It will be understood that a truck or any other vehicle may be equipped with the shutters and operated as the railway car illustrated in the drawing.

15 In the specific illustration given, the railway car is equipped with an intermediate floor 11, as shown in Figs. 2 and 3, so as to form two horizontal compartments in which animals may be placed for shipment. Each of the compartments is provided with a side door 12 through which the animals may be admitted, as illustrated in Fig. 1. It will be understood, however, that the railway car, or other form of live stock car, may have a single compartment. In the hauling of hogs and sheep, it is customary to divide the railway car into two compartments, while in the handling of larger animals such as cattle, the railway car has a single compartment. For the purpose of illustration, the invention will be described in connection with the live stock car illustrated in which two compartments are formed.

As illustrated best in Figs. 1, 2 and 5, shutter strips or louver boards 13 are connected in spaced relation by the metal straps 14. The shutter strips or sheets 13 may be formed of sheet metal or other suitable material. In the specific illustration given, the strips 13 are welded to the metal straps 14. If desired, the ends of the strips or louvers 13 may be cupped about the ends of the end straps 14 so as to form a reinforcement. However, any means of attachment of the strips 13 to the straps 14 may be employed and, if desired, the strips may be formed of plastic, wood or any suitable type of material.

45 Each of the shutter strips 13 has its upper end provided with an outwardly extending flange 15, as shown more clearly in Figs. 2 to 5 inclusive.

The shutter strips 13 or the straps 14 may be guided for vertical movement by any suitable means. In the specific illustration given, I provide Z-shaped bars 16 which are separated from the slats 10 by spacer members or washers 17, and a bolt 18 extends through a flange of the Z member 16, washer 17, and the slat 10. In 50 the illustration given in Fig. 4, the Z members

16 are spaced apart to provide a guide chamber 19 therebetween and adapted to receive a stabilizing slide member 20.

The stabilizing slide member 20 is equipped with a forwardly extending link 21 adapted to support a trough 22, as shown more clearly in Fig. 2. The trough 22 and the means for elevating the same, are shown more clearly in my co-pending application Serial No. 31,985, filed June 9, 1948.

The outer ends of the Z members 16, as shown more clearly in Fig. 4, provide guide recesses into which the shutters 13 and the end straps 14 extend. Thus, the shutter strips 13 normally lie in parallel horizontal alignment with the slats 10, as shown more clearly in Fig. 2, and the outwardly extending flanges 15 rest upon the tops of the slats to support the shutters 13 thereon.

Any suitable means for effecting vertical movement of the shutter members 13 may be provided. In the illustration given, I provide the straps 14 with flexible elements 23 which may be in the nature of chains, cables, link chains or any other suitable material. In the specific illustration given, the elements 23 consist of chains and are passed over sprockets 24 fixed upon a shaft 25.

At the ends of the car or, if desired, at any intermediate portion thereof, flexible elements 23 may be passed over sprockets 24 and provided with counter weights 26 or any other desired counterbalance means. The weights 26 may be housed within enclosures 27 which may be within the car or exterior of the car walls.

The shaft 25 may be connected to an actuating shaft 28 by worm and gear connections, as shown more clearly in Fig. 3, and the actuating shaft 28 may extend exteriorly of the car and may be provided with an operating wheel 29. Any suitable means for rotating the shaft 25 may be employed. The worm and gear connections are particularly advantageous in that they retain the shutters at any desired elevated position without the necessity of latching the members in position.

If desired, the counter weights may be omitted. Further, any suitable mechanism for raising and lowering the flexible elements 23 may be employed. The shaft 25 may be equipped with squared or polygonal ends for receiving a wrench or other means for rotating the shaft to elevate the shutters to a desired height and a pawl and ratchet means may be employed for supporting the shutters releasably in their desired positions.

Operation

In the operation of the apparatus illustrated, the shutter strips or louvre boards 13 normally lie in the position in which they are shown in Fig. 2 with the outwardly turned flange 15 of each resting upon the adjacent slat 10. Should any of the elevating apparatus hereinafter referred to break, the shutter strips will fall to this position in which the spaces between the slats are opened, thus avoiding any possibility of smothering or over heating of the live stock.

Should the temperature drop, or should driving snows, rain or cold winds be encountered, the car attendant may rotate the actuating shaft 28 so as to turn shaft 25 and sprocket wheel 24 for elevating the flexible elements 23 and straps 14. This operation, if carried to its limit, brings the flange 15 of each shutter strip against the bottom of the slat 10 thereabove, as shown

best in Fig. 3. If a fully closed position is not desired, the operator may raise the shutter strips so that the flange 15 is at an intermediate point between the slats. Upon releasing the operating wheel 29, shafts 25 and 28 remain stationary by reason of their worm and gear connections. The counter weight 16 is preferably a little less in weight than the weight of the shutter and strap structure so that if movement should occur during motion of the car, the weight of the shutters and straps will drive them downwardly to the open position illustrated in Fig. 2. The open position is the least dangerous, since there is always danger of smothering and over heating if the ventilation spaces are closed, and it is, therefore, desired that should there be a breakage or accidental movement of the elevating mechanism, the shutter strips will always seek the position shown in Fig. 2.

To restore the elevated shutter strips 13 to their initial position, the operator can readily turn the wheel 29 and, thereby, lower the shutters to the position shown in Fig. 2.

The apparatus is extremely compact, and the shutters are held snugly against the adjacent slats to prevent rattling. No projecting parts are provided which would injure animals or provide a hazard for railway traffic. The shutters can be moved to any desired position in an extremely brief time, and to meet any sudden change in weather conditions. In case of accident or breakage, the shutters will always fall to the open position illustrated in Fig. 2 in which there is the least possibility of harm to the live stock.

In the practice of the present invention, a single shutter strip may be employed or any desired number of shutter strips may be used. The number of shutters desired will vary with different types of cars. For the type of railway car illustrated, it is usually found that the three shutters illustrated for each compartment will be sufficient for controlling the ventilation of the compartment.

While in the foregoing specification I have set forth certain structures in considerable detail for the purpose of illustrating the invention, it will be understood that such details of structure may be varied widely by those skilled in the art, without departing from the spirit of my invention.

I claim:

1. In a livestock car having side walls equipped with spaced horizontal slats, a plurality of horizontal shutters, said shutters having their upper edges equipped with flanges extending forwardly into the space between said slats, means for raising and lowering said shutters in the space between said slats and including a depending strap secured to said shutters at spaced distances to support said shutters in spaced relation, said shutters having a width not substantially greater than the width of said slats whereby, when said shutters are allowed to drop, the top flanges of said shutters suspend said shutters behind said slats to open the spaces between the slats, and vertically-extending guide members carried by said car side walls and providing vertical guide recesses receiving the ends of said shutters, the ends of said shutters being supported within said guide recesses by said strap.

2. In a livestock car having side walls equipped with spaced horizontal slats, a plurality of shutters, each having a width not substantially greater than the width of the slats and having at its

top edge an outwardly-extending flange which extends into the space between the slats, guide means carried by said slats and comprising vertical members providing vertical recesses and receiving the ends of said shutters to guide said shutters in a vertical plane, and means for raising and lowering said shutters and including a vertical strap secured to said shutters at spaced points to support said shutters in spaced relation and the ends of the shutters within said vertical recesses.

3. In a livestock car having side walls equipped with spaced horizontal slats, a plurality of horizontal shutters secured together in spaced relationship, said shutters having their upper portions provided with flanges extending into the space between said slats, vertical members carried by said slats and providing guide recesses adapted to receive the end portions of said shutters and to guide them in a plane parallel with said slats, and means for raising said shutters into a position above said slats to close spaces between the slats and including a vertically-extending strap secured to said shutters at spaced points to support said shutters in spaced relation and to support the ends thereof within said guide recesses, said shutters, when permitted to fall, being suspended by the flanges thereof upon the slats below and opening the spaces between the slats.

4. In a livestock car having side walls equipped with spaced slats, a plurality of shutters equipped

5 at their upper ends with laterally-extending flanges adapted to be received within the spaces between said slats, whereby, when said shutters are released, they become suspended by the flanges thereof upon the slats therebelow, vertical Z-shaped members secured to the slats and providing guide recesses adapted to receive the ends of said shutters and to guide them in a plane parallel with the said slats, rigid strips secured to said shutters to maintain them in spaced relation and to support the ends of said shutters in said guide recesses, and flexible elements secured to said strips for raising and lowering the shutters.
